HENRY B. GREENOUGH, OF BEVERLY, MASSACHUSETTS, ASSIGNOR TO UNITED SHOE MACHINERY CORPORATION, OF PATERSON, NEW JERSEY, A CORPORATION OF NEW JERSEY.

NAIL-TRANSFERRING MECHANISM.

1,377,337.

Specification of Letters Patent. Patented May 10, 1921.

Application filed June 3, 1918. Serial No. 237,954.

To all whom it may concern:

Be it known that I, HENRY B. GREENOUGH, a subject of the King of Great Britain, residing at Beverly, in the county of Essex and State of Massachusetts, have invented 5 certain Improvements in Nail-Transferring Mechanisms, of which the following description, in connection with the accompanying drawings, is a specification, like reference characters on the drawings indicating like parts in the several figures.

This invention relates to mechanisms for transferring nails and is herein disclosed in a form adapted for supplying the nailing 15 mechanism of a heel-attaching machine from a nail-distributing mechanism.

An object of the invention is to provide 20 novel means to prevent the delivery of more than one charge of nails by the transfer mechanism between successive operations of the nailing mechanism. A movable work-engaging member, as a holder for heels and top lifts, controls in its movement the operation of the transfer mechanism, it preferably governing means which is arranged 25 to limit the movement of said transfer mechanism during its nail-transferring travel.

Another object of the invention is to furnish 30 novel means to avoid the delivery of more than one charge of nails to the transfer mechanism between successive deliveries to the nailing mechanism. There is shown for this purpose a device arranged to control the operation from the transfer mechanism 35 of the distributing mechanism which supplies nails to said transfer mechanism, said device including means which delays, until a complete delivery by the transfer mechanism has been made, the operation of the 40 distributing mechanism.

I have chosen in the accompanying drawings to illustrate my invention adapted for use in connection with a heel-attaching machine which may be arranged to drive nails 45 in either of two directions, which is the subject of an application for Letters Patent of Benjamin F. Mayo, filed June 3, 1918, Serial No. 237,951. It is to be understood, however, that my improved transfer mechanism is not confined in its application to 50 machines of this character.

Figure 1 of the drawings is a side elevation, parts being broken away, of this in-

vention arranged for delivering nails to a machine organized for upward nailing, the 55 transfer mechanism being in the nail-receiving position.

Fig. 2 is a broken top plan view of the same; and

Fig. 3 is a view similar to Fig. 2 with the 60 parts adapted for downward nailing but with the transfer mechanism in its delivery position.

The only essential difference between the 65 two forms of the invention is the vertical relation of certain of the elements, especially those of the heel and top lift holding mechanism. In Figs. 1 and 2 they are above the heel-attaching mechanism, and in Fig. 3 below it.

Referring more particularly to Figs. 1 and 2 of the drawings, in horizontal ways 260 in a supporting member 256 secured to the frame 22 of a heel-attaching machine is a nail block 54 provided with the usual nail 75 receiving openings 262. Pivoted by a spindle 264 on the support to move across the nail block is a heel and top lift swing plate 266, on which are mounted the adjustable heel fork 268 with its breast gage 270 and 80 the top lift fork and gage 272 and 274, respectively. Fixed to the spindle carrying the swing plate and on the opposite side of the support is a lever having arms 276 and 278. A spring 280 joins the arm 276 to the 85 support 256, drawing the swing plate about its pivot until it contacts with the yieldable stop 282, such as is customarily provided in connection with such mechanisms and which is arranged to cushion the blow of the plate 90 against it. The arm 278 has pivoted upon it a latch 284 with its engaging point arranged to normally contact in the movement of the swing plate with a projection 286 fixed to the adjacent face of the support 256. A 95 spring 288 is seated in a vertical recess in a boss 290 depending from the lever to hold the point of the latch in its raised position. To lower the point of the latch to release it from the projection 286, the tail 292 is struck 100 by a projection 294 carried by the nailing head 53 when it rises in its nail driving movement.

On a bracket 296 bolted to the side of the support 256 is mounted a vertical spindle 105 298, about which turns a loader arm 300

carrying at its outer extremity a separable loader block 302, in which are perforations 303 arranged in the form in which the nails are to be driven into the heel operated upon. 5 Pivoted at 304 beneath the block is a loader gate 306 upon which rest the ends of the nails delivered to the openings in the perforations 303. From a projection 308 from the gate to the loader arm extends a helical spring 310, the force of which is exerted to turn the gate about its pivot 304 from beneath the loader block. The gate is held normally in its position beneath the block by a latch 312 pivoted at 314 on the loader arm and drawn by a spring 316 between its tail 318 and the arm into engagement with a pin 320 on the gate. The loader arm may be swung by its handle 322 to opposite extreme positions, determined by contact of 10 adjusting screws 324 in short arms 326, 328 with opposite faces of a stop arm 330 upon the bracket 296. When the arm 326 co-operates with the stop, the loader arm is in such a position that the openings 303 are 15 alined with the usual nail tubes 332 supported upon a holder 334 fixed to an arm 336 at the top of the spindle 298. To the tubes 332 nails are delivered from a suitable distributing mechanism, of which the tubes and their holder may be considered a portion. The 20 distributing mechanism is tripped to cause it to deliver a charge of nails to the tubes 332 by a rod 342 guided by an arm 344 secured to the spindle 298. To insure the loader occupying the desired position when it receives its load of nails, a latch 346 is 25 pivoted at 348 on the arm 300 and is moved by a compression spring 350, situated in a bore on the arm and contacting with the tail of the latch, so that its pointed end 352 enters a recess of the spindle. When the arm is swung to the left, the inclined face 354 of the engaging end of the latch permits it to 30 be drawn out of the recess without great resistance, and the loader block passes over the nail block 54 until the openings 262 and 303 are alined, at which time the screw of the arm 328 is in contact with the stop arm 330. 35 The parts of the heel and top lift holding 40 and the loading mechanisms being initially as illustrated in Fig. 2, with the block 302 supplied with a load of nails, upon swinging the loader arm toward the delivery position (Fig. 3), the side 355 of an angular end portion 356 of an arm 358 secured beneath the loader arm strikes a roll 360 upon the arm 276. This turns the swing plate 266 and its supporting spindle 264 until the latching projections 284 and 286 engage to 45 hold the plate with the heel fork and breast gage in that position with respect to the nail block in which a heel held between them is ready to have the heel seat of the shoe upon the usual jack pressed against it. As the 50 openings 303 in the loader block come into

alignment with those in the nail block 54, a curved face 499 on the loader gate latch strikes a pin 500 rising from the side of the swing plate, withdrawing the latch from engagement with the pin 320. This releases 55 the loader gate, allowing the spring 310 to withdraw it from beneath the openings 303, delivering the nails to the openings in the nail block 54. The loader arm is now swung back to its normal position and a heel and a top lift are placed between the forks and gages of the swing plate. In the travel of the loader mechanism, a face 366 of the arm 308 of the loader gate, which arm is now in a position substantially at right angles to 60 the latched relation shown in Fig. 2, or as it appears in Fig. 3, comes into contact with a roll 368 mounted upon the rear of the upper face of the support 256. This resets the gate by moving it until the pin 320 is again 65 engaged by the latch 312. A cam member 370 fixed to the upper side of the loader arm contacts with the rod 342 and trips the mechanism of the nail distributor 338. This takes an appreciable time to operate, so that 70 not until the arm 326 has reached the stop 330 is the load of nails delivered from the tubes 332 to the loader block. When under the influence of the actuating mechanism, the driver head rises to project the drivers 75 into the openings in the nail block and drive the nails through the heel into the jacked shoe, the projection 294 on the head contacts with the tail 292 of the swing plate latch. The latch is thereby moved out of contact 80 with the projection 286 upon the support, permitting the spring 280 to shift the swing plate to the position illustrated in Fig. 2, in which a top lift is brought under the heel attached to the shoe, from which the driven 85 nails have been left projecting. The portion 372 of the swing plate is now interposed between the driver head and the top lift to 90 serve as a spanker plate.

Were the loader arm to be moved more 95 than once from its nail receiving to its nail delivering position between nailing operations, the first load would be properly introduced into the openings 262 of the nail block, while the succeeding loads would fall 100 upon the swing plate and support and possibly interfere with the action of the machine. Means is provided for positively preventing this plural delivery, consisting of 105 a stop arm 374 mounted to turn upon the spindle 264 and drawn against a pin 376 upon the arm 276 by a spring 378 joining the stop arm with a point upon the support. This arm 374 has a contact portion 380, which, in the first movement of the loader 110 mechanism in which the swing plate is shifted to bring the heel holder to the nail block, is so situated that it does not interfere with such movement, the portion 382 of the arm 358 contacting with the edge of 115

the stop arm to turn it about the spindle 264 against the tension of the spring 378. After the swing plate has been turned on its pivot and latched by the elements 284 and 286, the 5 portion 380 lies upon the arc through which moves the portion 382. It therefore catches and holds the arm 358, the contact of the face 355 of the extension with the end of the arm 374 preventing the rotation of the latter about the spindle.

Difficulty may also be experienced in the use of a nail loading mechanism as a result of making an incomplete movement of the loader arm from its receiving to its delivering position. Since the load of nails in the block 302 would not be discharged as a result of the contact of the gate latch 312 with the pin 500 of the swing plate, the return of the loader mechanism to its initial position would cause the distributing mechanism to drop a second load of nails upon the already filled openings of the loader block, unless there is means for preventing this. Such means is here provided 20 in the actuating member 370 carried by the loader arm to raise the rod 342 for tripping the distributing mechanism. This actuating member is in the form of a cam block, shown as curved along the arc through 25 which it travels into coöperation with the rod. As the arm swings to the left in Fig. 3 in the delivering movement of the loader mechanism, a pivoted contact portion 381 at the lower extremity of the rod yields so that 30 said rod is not lifted and the distributing mechanism is not affected. When the arm 370 has passed the rod, the portion 381 straightens and upon the return of the loader arm acts as a rigid continuation of 35 the rod. As the inclined end 384 of the cam travels beneath the rod during the return, the latter is raised and is held as long as the extended arcuate portion of the cam is beneath it, thereby tripping the distributor mechanism to cause it to discharge the succeeding load of nails to the loader block when its openings are alined with tubes 332. The relation of the cam to the loader arm 40 is such that it does not clear the end of the rod 342 in its movement to the left until the loader mechanism has reached its delivery position, in which the loader gate has been released and the load of nails supplied to the nail block. Consequently for any incomplete movement, in which the nails are retained by the loader mechanism, the portion 45 381 does not straighten, the rod is not raised and the distributing mechanism cannot doubly load the block 302.

60 In the travel of the loader arm from its receiving to its delivering position, it is necessary to carry it above the heel holder until the arm has cleared this and is over the nail block. For this purpose, the hub 65 of the arm 300 has a downward arcuate pro-

jection 502 riding over a corresponding upward projection 504 upon the arm 296. The contact of these projections maintains the proper raised relation until the loader block passes the heel holder, at which time the 70 projection 502 has moved beyond projection 504 and a roll 506 rotatably mounted between lugs beneath the loader arm travels down an incline of a cam member 508 fixed at the right and near the rear of the support 75 256. This brings the loader block gradually to its correct vertical relation to the nail block. When the opposite movement occurs the contact between the roll and incline raises the arm until the projection 502 is 80 above its companion projection 504, so that during the remainder of the travel in this direction these projections support the loader mechanism to clear the heel holder.

Having fully described my invention, 85 what I claim as new and desire to secure by Letters Patent of the United States is:

1. In a machine of the class described, the combination with nailing mechanism, of mechanism for transferring nails to the 90 nailing mechanism, a movable work-engaging member coöperating with the nailing mechanism, and means controlled by said member and arranged to limit the movement of the mechanism during its nail-transferring travel.

2. In a heeling machine, the combination with nailing mechanism, of mechanism for transferring nails to the nailing mechanism, a movable work-engaging member coöperating with the nailing mechanism, and means coöperating with said member adjacent to its nail-delivering position for preventing the delivery of more than one charge of nails for a single operation of the 105 nail-transferring travel.

3. In a heeling machine, the combination with a nail block, of a movable loader mechanism for delivering nails to the block, a movable holder coöperating with the nail 110 block, and means moved by the holder to a position limiting the movement of the loader mechanism.

4. In a heeling machine, the combination with nailing mechanism, of mechanism for 115 transferring nails to the nailing mechanism, a work-engaging member coöperating with the nailing mechanism in a plurality of positions, connections to the transfer mechanism for moving said member to one of its 120 positions, and means controlled by the work-engaging member in its movement under the influence of the transfer mechanism for preventing the delivery of more than one charge of nails until said member has occupied a 125 plurality of positions.

5. In a heeling machine, the combination with nailing mechanism, of mechanism for transferring nails to the nailing mechanism, a movable presenting member coöperating 130

with the nailing mechanism, and a stop moved by the presenting member into the path of the transfer mechanism.

6. In a heeling machine, the combination 5 with nailing mechanism, of mechanism for transferring nails to the nailing mechanism, a movable presenting member coöperating with the nailing mechanism, and a stop moved by the presenting member into the 10 path of the transfer mechanism and being yieldable upon contact of the transfer mechanism in certain of its movements.

7. In a heeling machine, the combination 15 with a nail block, of a movable loader mechanism for delivering nails to the block, a movable holder coöperating with the nail block, and means mounted in proximity to the holder to move therewith for preventing the coöperation of the loader and block before the nails delivered have been discharged 20 from the block.

8. In a heeling machine, the combination 25 with a nail block, of a movable loader mechanism for delivering nails to the block, a holder movable across the block, and a stop arm movable by the holder into position to contact with the loader mechanism.

9. In a heeling machine, nailing mechanism, nail loading mechanism, a swing 30 plate having heel and top lift holders movable into coöperation with the nailing mechanism, and a stop arranged to swing with the plate, said stop coöperating with the loader mechanism when the top-lift holder 35 coöperates with the nailing mechanism and being ineffective when the heel holder coöperates with the nailing mechanism.

10. In a heeling machine, nailing mechanism, nail loading mechanism, a spindle situated adjacent to the nailing mechanism, a swing plate fixed to the spindle, and an arm mounted upon the spindle, the arm being movable with the swing plate to vary its coöperation with the loading mechanism.

45 11. In a heeling machine, nailing mechanism, nail loading mechanism, a spindle situated adjacent to the nailing mechanism, a swing plate fixed to the spindle, and an arm yieldably mounted upon the spindle and coöperating with the loading mechanism.

50 12. In a heeling machine, nailing mechanism, nail loading mechanism, a spindle situated adjacent to the nailing mechanism, a swing plate fixed to the spindle, an arm mounted to turn upon the spindle, and a spring to maintain the normal position of the arm, said arm being rotatable with the spindle under the influence of the loading mechanism.

55 60 13. In a heeling machine, nailing mechanism, nail distributing mechanism, mechanism for receiving nails from the distributing mechanism and transferring them to the nailing mechanism, and a device arranged to control the distributing mecha-

nism from the transfer mechanism, said device including means for delaying the operation of the distributing mechanism until a full delivery movement of the transfer mechanism has been made.

70 14. In a heeling machine, nailing mechanism, nail distributing mechanism, mechanism for receiving nails from the distributing mechanism and transferring them to the nailing mechanism, a member movable with 75 the transfer mechanism for initiating the operation of the distributing mechanism, and a member connected to the distributing mechanism with which said initiating member contacts actively only upon the return 80 movement of the transfer mechanism.

15. In a heeling machine, nailing mechanism, nail distributing mechanism, mechanism for receiving nails from the distributing mechanism and transferring them to the 85 nailing mechanism, a member movable with the transfer mechanism for initiating the operation of the distributing mechanism, and a member connected to the distributing mechanism with which said initiating member contacts actively only after the transfer 90 mechanism has completed its delivery movement, such contact continuing during a portion of the return movement of the transfer mechanism.

95 16. In a heeling machine, nailing mechanism, nail distributing mechanism, mechanism for receiving nails from the distributing mechanism and transferring them to the nailing mechanism, a member movable with 100 the transfer mechanism for initiating the operation of the distributing mechanism, and a member connected to the distributing mechanism with which said initiating member contacts idly as the transfer mechanism approaches the end of its delivery movement and actively upon the return movement after the charge of nails has been delivered to the nailing mechanism.

105 17. In a heeling machine, a nail block, a nail distributor having an actuating rod provided with a pivoted end, a loader mechanism having a loader block movable between the distributor and nail block, and a cam movable with the loader mechanism and contacting with the pivoted end of the rod when the loader block is adjacent to the nail block.

115 18. In a heeling machine, a nail block, a nail distributor having an actuating rod provided with a pivoted end, a loader mechanism having a loader block movable between the distributor and nail block, and a cam movable with the loader mechanism and contacting with the pivoted end of the rod when the loader block is adjacent to the nail block, 120 said cam being extended from such point of contact toward the distributor.

125 19. In a heeling machine, a nail block, a nail distributor having an actuating rod provided with a pivoted end, a loader mecha-

nism having a loader block movable between the distributor and nail block, and a cam movable with the loader mechanism and contacting with the pivoted end of the rod when 5 the loader block is adjacent to the nail block, said end yielding upon contact with the cam during the movement of the loader block toward the nail block and acting as a rigid extension of the rod during the return movement of the loader block.

20. In a heeling machine, nailing mechanism, nail distributing mechanism, mechanism for receiving nails from the distributing mechanism and transferring them to the

nailing mechanism, means for preventing 15 the delivery of more than one charge of nails to the nailing mechanism between successive operations thereof, and means for preventing delivery of more than one charge of nails to the transfer mechanism between successive 20 deliveries to the nailing mechanism, both the preventing means becoming effective at one extreme of travel of the transfer mechanism.

In testimony whereof I have signed my 25 name to this specification.

HENRY B. GREENOUGH.
